UNITED STATES PATENT OFFICE.

BENJAMIN F. BELLows, OF CLEVELAND, OHIO, ASSIGNOR TO THE ELECTRIC COMPOSITOR COMPANY; OF NEW YORK, N. Y., A CORPORATION OF NEW JERSEY.

LINOTYPE-MAKING MECHANISM.

No. 921,064.

Specification of Letters Patent.

Patented May 11, 1909.

Application filed August 16, 1906. Serial No. 330,775.

To all whom it may concern:

Be it known that I, BENJAMIN F. BELLows, a citizen of the United States, residing at Cleveland, in the county of Cuyahoga and State of Ohio, have invented a certain new and useful Improvement in Linotype-Making Mechanism, of which the following is a full, clear, and exact description.

This invention is especially adapted for use as part of a linotype machine for the purpose of casting the linotype from an assembled line of matrices, for trimming the sides of said linotype, and for delivering the finished linotype into a galley or some other suitable receptacle. The invention may be summarized as the construction and combination of parts hereinafter described and pointed out definitely in the claims.

In the drawing Figure 1 is a front elevation of mechanism embodying the invention, when the trimming knives and their support have been removed, and when a part of the mechanism for transferring the finished linotype to the galley has been broken away. Fig. 2 is a front elevation of said trimming knives and their frame, and fragments of the transferring mechanism. Fig. 3 is a transverse vertical section in the plane indicated by line 3—3 on Fig. 4. Fig. 4 is a plan view of the invention. Fig. 5 is a front elevation, partly broken away, of the trimming knives frame, the trimming knives and the parts immediately associated therewith. Fig. 6 is a sectional plan in the horizontal plane of the mold slot, at the right end of the knife frame; this figure being for the purpose of showing the trimming knife I and the wipers near it. Fig. 7 is a transverse sectional elevation in the plane indicated by line 6—6 on Fig. 4. Fig. 8 is a transverse sectional view of certain parts of the mechanism, in the plane indicated by line 8—8 on Fig. 4.

Referring to the parts by reference letters, A represents the mold block which is removably secured in a recess in the slide B. This slide is mounted between horizontal guide rails c c of the frame member C, so that it may move backward and forward in the horizontal path from a position in which the mold is alined with the trimming knives D—D', and a position in which said mold is alined with a pot nozzle L.

The trimming knives are adjustably

mounted in a frame E which is removably secured to the front face of frame C. The mold block A has the usual mold slot a; and this block is removably held in the recess, to which it is fitted, in slide B, by means of spring-actuated taper ended pins G—G'. These pins are mounted in the ends of the slide, in position substantially as shown, whereby they may engage in tapered holes in opposite ends of the mold block. Suitable means may be provided for withdrawing both pins so as to permit the removal of the mold block. The mechanism shown for this purpose consists of a rocker g pivoted at one end to the head g' of pin G, and at its other end to a longitudinally movable rod g² which passes entirely through the slide and engages with the head g³ of the other pin G'. The pivots connecting this rocker with the parts mentioned must fit loosely either in the rocker or other part whereby, when the rocker is rocked in one direction, it will first withdraw one of said pins G—G',—whichever is withdrawn most easily, and will thereafter, by continuing its motion, withdraw the other pin.

The slide B may be moved backwardly or forwardly in the path mentioned by any suitable mechanism. As shown a lever H is connected by link h with the slide. This lever is on the rock-shaft h' to which also is attached an arm h² having a friction roller h³ in its end. This friction roller is engaged by cam k attached to the rotatable shaft K, and thereby the rock-shaft h' is so rocked that the slide B is moved to the left, that is to say, to the position which brings the mold in proper alinement with the trimming knives. A spring h⁴ engaging with the arm h⁵ serves to rock the rock-shaft h' in that direction which will move slide B to the other end of its path, viz; into position between the pot nozzle L and a line of matrices M. The mechanism for moving the matrix line and the pot nozzle against opposite faces of the mold may be of any suitable construction as, for example, like that shown in my prior patent No. 791,747. The spring-actuated movement of the slide is limited and rendered definite by the engagement of the end of the slide with a part c⁷ of the guide frame.

The frame C in which the mold slide B moves may be provided with passages c² c³

- which extend horizontally in the overhanging rear parts of the frame members $c-c'$, and are connected through a vertical passage c^4 in a vertical part c^5 of said frame.
- 5 By means of suitable pipe connections with the left ends of the two passages c^2 c^3 cold water, for the purpose of keeping the mold and mold slide cool, may be circulated through these water-ways.
- 10 The trimming knives D—D' are, as before stated, supported in a frame E. This frame has upon its lower member two inclines e and e' for engagement with corresponding inclines d and d' carried by the 15 lower knife block. The upper member of this frame has the inclines e^2 and e^3 for engagement with inclines d^2 d^3 carried by the upper knife block. The angle of the inclines associated with the upper knife is 20 greater than that of the inclines associated with the lower knife. The inclines carried by the knife blocks may be the ends of adjustable screws d^4 which screw through the knife blocks. When these knives are in the 25 frame they are separated as far as possible by the action of springs N seated in recesses d^5 in the proximate faces of the knife blocks. A set-screw d^6 which screws through the end of the frame E bears 30 against the ends of both knife blocks so as to move them simultaneously and equally in the frame. The result will be that the parallelism of the knife edges will be preserved, while the distance between them will be 35 changed to adapt the knives for trimming slugs of different thicknesses. It will, of course, be understood that when the distance between the knife blades is changed the mold block A will be taken from slide B 40 and another mold, having its slot a of a different width, substituted. The slots in the different mold blocks are so placed that it is desirable to have the upper knife block move downward farther than the lower 45 knife block moves up, when the distance between said knife blocks is reduced. It is for this reason that the inclines e^2 and e^3 are made steeper than the inclines e and e' .
- A gage block X is adjustably secured to 50 the outer end of the adjusting screw, and on it are graduation marks to be read in connection with other marks on the knife frame. To adjust the gage block, a linotype of the desired thickness is placed between the 55 knives, which are then moved against said linotype. The gage block is then moved to and secured in the position when a definite mark thereon registers with a mark on the frame. The knives may be moved away 60 from this position whenever desired, and then restored to this position by again turning the screw to bring the graduation marks referred to into line. These knife blocks are held in the frame by means of plates e^7 65 secured to the front face of said frame and

plates e^8 secured to the rear face of said frame. All of these plates, however, lap over and engage with the outer faces of the respective knife blades.

After a linotype has been formed in the 70 mold, and said mold has been moved into range of the trimming knives, said linotype is to be pushed from the mold and between these trimming knives by an ejector P. The knife frame E is secured to the front face 75 of the frame C in which slide B moves. The ejector blade is removably clamped to a slide Q, which is mainly supported on guide rails c^9 , but which preferably has a depending arm q which is slidably mounted upon the 80 shaft R by which it is additionally guided. Preferably some mechanism for moving this ejector slide will be provided, but any suitable mechanism may be employed.

When the finished linotype is ejected 85 from the mold, and pushed through the trimming knives it is delivered to a transferring device T. This device has an arm having in it a longitudinal slot t whose front wall is beveled or rounded off as shown at t' . 90 The linotype is pushed entirely across this slot by the ejector blade, and left with its forward edge resting upon the beveled top of said arm. When the ejector is withdrawn, the rear edge of the linotype, being 95 unsupported, will fall by gravity down into said slot. This slot is inclined downward toward its outer end, at an inclination sufficient to cause the linotype to slide out of it if permitted so to do. A spring-actuated 100 retaining dog S is pivoted to the arm, and has a toe s extending in front of the open end of said slot. Adjacent to the other end of this dog there is a slot t^2 in the arm adapted to receive a fixed tripping pin U. 105 The arm T is secured to a sleeve t^3 which is rotatably mounted upon a vertically movable shaft W. This sleeve has in it a spiral groove t^4 into which projects a fixed pin U'. An arm w fastened to this shaft carries a 110 friction roller w' which rests upon a cam w^2 attached to the rotating shaft K, and the action of this cam is to lift the shaft and sleeve, whereby, through the interaction of said pin U' and spiral groove t^4 , the sleeve 115 is turned to a position where the linotype in slot t may slide out of the same into a galley or other receptacle. When said sleeve t^3 has been turned in the manner stated, the rear end of dog S will be brought into contact 120 with pin U, and, thereby, this dog will be so swung as to release the linotype, and permit it to slip out of the slot in said arm.

It is desirable, and perhaps necessary, that 125 both faces of the mold block and both trimming knives and pot nozzle shall be wiped after each use thereof. For this purpose four wiping devices are provided, two of them F and J are pivoted to the fixtures C, and are for the purpose of wiping the oppo- 130

site faces of the mold. The two other wipers O and Z are pivoted to the mold slide B and are for the purpose of wiping the trimming knives and nozzle respectively. These wipers 5 are alike in that each includes a frame which is pivoted on a vertical axis to the movable slide B or to a fixed part of the device, and has a wiper arm, and carries a friction producing device. When the wiper frame is 10 pivoted to the slide B, this friction producing device carried by the wiper frame engages with a fixed part of the frame; and when the wiper is pivoted to a fixture, this friction producing device engages with the 15 movable slide B. The movement of the slide, therefore, causes friction between the friction producing device and the part with which they engage, with the result of causing the wiper frames to swing upon their 20 pivots and move their wipers either against the part to be wiped or away from that part, as the case may be. The wiper frame F is pivoted to the top and bottom members c c' of the frame C. The top and bottom 25 members of said frame being connected by a member f which lies close to the rear face of the mold, and has a wiper pad f' for engaging with said mold face both above and below the mold slot; and said frame 30 carries a spring-actuated friction pin f² which passes through a relatively large hole in the top frame member c and engages with the top of the slide B. The wiper frame J is pivoted to the knife frame E and has a 35 wiper arm j for engagement with the front face of the mold. This frame also carries a spring-actuated friction pin j' which engages with the slide B. When the slide moves to the right, these wiper frames will 40 be moved upon their pivots by the friction so as to carry their wiper arms respectively against opposite faces of the mold. When the slide is moved in the other direction these wiper frames are rocked in the other 45 direction.

The wiper frame O is pivoted to slide B and has a wiper arm o, for engagement with knife blades, and a spring-actuated friction pin o' for engagement with the lower frame 50 member c'. The movement of slide B to the left causes the wiper frame to so swing that the wiper arm will engage with and wipe the knife blades. When the slide moves in the other direction the wiper frame is so 55 swung that the wiper arm is withdrawn from contact with the knife blades.

The wiper frame Z is pivoted to slide B, near the right end of the same as shown in Figs. 4 and 6. It carries a wiper z' for 60 engagement with the front face of the pot nozzle. It carries a friction pin z² which engages with one of the fixed frame members c c'. When the slide B moves to the right, the friction between the pin z² and 65 the frame member causes the frame to

swing upon its pivot so as to carry the wiper 2 against the face of the pot nozzle. When the slide B moves to the left this frame swings in the opposite direction.

A knife I is fixed in the frame member 70 c⁵, and it is placed in such position that it engages with the rear face of the mold in the line of the slot therein, and thereby trims the bottom of the linotype in said mold slot, when the mold is being moved 75 from the casting position to the ejecting position.

Having described my invention, I claim:

1. In a linotype machine, the combination 80 of a horizontal guide frame, a slide movably mounted therein, mechanism for reciprocating said slide within said guide frame, a mold block removably secured to said slide, a knife frame fixed to said guide frame, and trimming knives adjustably held within 85 said knife frame.

2. In a linotype machine, the combination 90 of a horizontal guide frame, a slide movably mounted therein, mechanism for reciprocating said slide, a mold block removably secured to said frame, a knife frame fixed to said guide frame, trimming knives within said knife frame, and means for simultaneously adjusting said knife blades toward and from each other. 95

3. In a linotype machine, the combination 100 of a frame having parallel guideways, a mold slide movable in said guideways, mechanism for reciprocating it, a mold in said slide, a knife frame secured to said guideway frame, trimming knives carried by said frame, and an ejector.

4. In a linotype machine, the combination 105 of a fixed frame having top and bottom members and a vertical member connecting them, which members contain connected passages for the circulating of water, a horizontally movable slide mounted in said frame between the top and bottom members thereof, a mold carried by said slide, and mechanism for reciprocating said slide within said guide frame. 110

5. In a linotype machine, the combination 115 of a knife frame having inclined surfaces, a pair of knives within said frame carrying surfaces engaging with the inclined surfaces on the frame, and mechanism for simultaneously moving said knives lengthwise in said frames.

6. In a linotype machine, the combination 120 of a knife frame having inclined surfaces, a pair of knives within said frame carrying surfaces engaging with the inclined surfaces on the frame, and mechanism for simultaneously moving said knives lengthwise in 125 said frames, a spring acting to separate said knives and hold said inclined surfaces in contact.

7. In a linotype machine, the combination 130 of a pair of trimming knives respectively

- provided with inclined surfaces, a frame within which said knives are movably fitted, which frame is provided with inclined surfaces for coöperating with the inclined surfaces carried by one knife, and having other and differently inclined surfaces for engagement with the inclined surfaces carried by the other knives,—and mechanism for simultaneously moving said knives longitudinally within said frame.

8. In a linotype machine, the combination of a knife frame having the inclined surfaces $e\ e'\ e''\ e'''$, two trimming knives movably fitted within said frame each having adjustable screws for engagement with two of said inclines, springs operating to thrust the knives apart, and mechanism for simultaneously moving said knives lengthwise in said frame.

9. In a linotype machine, the combination of a knife frame provided with inclined surfaces, a pair of knives movably fitted within said frame and carrying inclined surfaces for engagement with the inclined surfaces of the frame, and a screw which is screwed through one end member of said frame into engagement with the end faces of both trimming knives.

10. In a linotype machine in combination with the mold, the trimming knives, and the ejector which pushes the linotype out of the mold and through said trimming knives, with a receiver which occupies a position to receive the linotype when so pushed from between said knives, and mechanism for moving said receiver from the receiving position to a discharging position, mechanism preventing the linotype from falling out of said receiver, and mechanism for withdrawing said restraining mechanism when the receiver has reached the discharging position.

11. In a linotype machine, the combination of a vertically movable sleeve having an external spiral slot, and arm carried thereby containing a linotype-receiving channel, a fixed pin entering said spiral groove, and mechanism for moving the sleeve endwise.

12. In a linotype machine, the combination of a vertically movable sleeve having an external spiral slot, an arm carried thereby containing a linotype receiving channel, a fixed pin entering said spiral groove, and mechanism for moving the sleeve endwise, with a dog pivoted to said arm and extending normally over the end of the channel therein, and a fixed pin with which the tail of said dog will engage when said arm has reached the discharging position.

13. In a linotype machine, the combination of a vertically movable sleeve having a spiral groove and provided with an arm in which is a linotype receiving channel, which channel is inclined downward toward the outer end of said arm, a spring-actuated dog pivoted to said arm and extending across the outer end of said channel, a fixed pin entering said spiral groove, means for moving this sleeve endwise, and a fixed device for engaging with and releasing said dog when the sleeve has swung the arm to the discharging position.
